US00D755720S

(12) **United States Design Patent**
Dobler

(10) **Patent No.:** **US D755,720 S**
(45) **Date of Patent:** **** May 10, 2016**

(54) **CONNECTOR**

(71) Applicant: **NEUTRIK AG**, Schaan (LI)

(72) Inventor: **Oliver Dobler**, Eschen (LI)

(73) Assignee: **Neutrik AG**, Schaan (LI)

(**) Term: **14 Years**

(21) Appl. No.: **29/487,575**

(22) Filed: **Apr. 10, 2014**

(30) **Foreign Application Priority Data**

Oct. 14, 2013 (EP) 001 386 684-0001

(57) **CLAIM**

The ornamental design for a connector, as shown and described.

DESCRIPTION

FIG. 1 is a perspective view of a connector showing my design;

FIG. 2 is a left side elevation view thereof;

FIG. 3 is rear elevation view thereof;

FIG. 4 is front elevation view thereof;

FIG. 5 is a top plan view thereof;

FIG. 6 is a right side elevation view thereof; and,

FIG. 7 is a bottom plan view thereof.

The broken line portions of the figures are included to show unclaimed subject matter only and form no part of the claimed design.

1 Claim, 2 Drawing Sheets
